UNITED STATES PATENT OFFICE.

JOHN BERRY KELLY, OF BIRMINGHAM, ALABAMA, ASSIGNOR OF ONE-HALF TO Z. A. DOUGLAS, OF BIRMINGHAM, ALABAMA.

RAILROAD-TRACK SAND-REMOVER.

1,222,213.

Specification of Letters Patent. Patented Apr. 10, 1917.

Application filed November 27, 1916. Serial No. 133,730.

To all whom it may concern:

Be it known that I, JOHN BERRY KELLY, a citizen of the United States of America, residing at Birmingham, in the county of 5 Jefferson and State of Alabama, have invented certain new and useful Improvements in Railroad-Track Sand-Removers, of which the following is a specification.

My invention relates to a railroad track sand remover for use with steam or electric locomotives which is constructed and attached to the locomotive so that it will discharge a fluid jet either water, steam or air against the surface of the rails immediately 10 behind the rear driving wheels of the locomotive to blow the sand from the rail after the driving wheels have passed over it and in advance of the wheels of the train. My apparatus is controllable so that it can be 15 used when desired and its principal use will be when the rails have been heavily sanded in pulling up grades. If sand is left on the track after serving its function under the driving wheels, the other wheels of the train 20 will have to run over it so that the wheel friction will be increased and the grinding wear on both the wheel tread and flange, and particularly on the rails, will be greatly increased. If simple, inexpensive and effective 25 means can be provided for removing this source of friction and wear after the sand has served its useful function, a substantial increase in the life of both wheels and rails will result and the friction between the wheels and rails will be reduced 30 to a minimum, thereby increasing the tonnage that can be hauled.

My preferred means for removing the sand from the rails is a thin high pressure 35 jet of water from the locomotive boiler but it is within the contemplation of my invention that the results contemplated can be accomplished by a flush of water from the water tank on the tender or by other like 40 means. The stream of water should be directed away from the wheels and machinery of the locomotive to avoid causing rust and the formation of masses of ice thereon.

My invention further comprises the novel 45 details of construction and arrangements of parts, which in their preferred embodiments

only is shown in the accompanying drawings, in which:

Figure 1 partially illustrates a locomotive in side elevation equipped with my invention. 55

Fig. 2 is a rear elevation of Fig. 1.

Fig. 3 is a view similar to Fig. 1 showing my invention adapted to work with air.

Fig. 4 shows my invention as applied to 60 the tender for flushing the track from the water tank thereon.

Similar reference numerals refer to similar parts throughout the drawings.

I have illustrated my invention as applied to a steam locomotive 1 but it will be understood that this is typical of any type of locomotive. The locomotive is provided with a sand box 2 and sander pipe 3 disposed to deliver sand in advance of the locomotive driving wheels 4 which are shown running on the track rails 5. I tap into the side of the boiler 6 of the locomotive, preferably below the water line therein which is indicated by the dotted line Fig. 2, a 65 pipe 7 which is connected by an elbow to a pipe 8 leading down through the floor of the cab 9. I provide a valve 10 to control the flow of water or steam and water from the boiler to the pipe 8 and dispose it in 70 convenient reach of the engineer in the cab. This pipe 8, after passing below the floor of the cab, is inclined rearwardly so as to extend down immediately behind the rear driver 4 and there by means of a T-fitting 75

11 it is connected to a jet pipe 12 on one side and also to a cross pipe 13 passing under the locomotive and connecting by an elbow to a jet pipe 12 on the other side of the locomotive. These jet pipes 12 are disposed 80 closely behind the rear driving wheels 4 and at their lower ends are flattened to form wide narrow jet nozzles 14 which are disposed adjacent to rail treads and given a rearward inclination so as to deliver slanting jets of water rearwardly to sweep the rails clean of the sand. These several pipes can be secured in any suitable manner to the frame of the locomotive. By opening the valve 10 it will be apparent that the 85 sand after passing the drivers 4 is removed from the track rails and the latter are left

clean before the other wheels of the train pass thereover, thereby increasing the tonnage hauling capacity of the locomotive.

In Fig. 3 I show the locomotive equipped 5 with a main air reservoir tank 15 forming part of its air brake system, the other details of which are omitted as forming no part of my present invention. From this main reservoir I lead a pipe 16 into the cab 10 and provide therein a valve 17 to control the delivery of air from the pipe 16 to the pipe 18 which leads down through the floor of the cab like the pipe 8 and this pipe 18 is connected by means of the T-fitting 11 and 15 a cross pipe 13 (as shown in Fig. 2) to the jet pipes 12 which will deliver the air jets through nozzles 14 in the same manner that the pipes 12 of Fig. 1 deliver the water jets to clean the rail treads.

20 In Fig. 4 I show a locomotive tender 19 of a standard design and in the water reservoir therein I provide a valve casing 20 equipped with a valve of any suitable type which is controlled by a stem 21 that passes 25 up through the top of the tank and in convenient reach of the fireman or engineer. When the valve is opened a flush of water from the tank in the tender will flow through a pipe 22 to the T-fitting 11 and 30 will flow therefrom by the piping arrangements already described to the jet nozzle 23, which are formed similarly to the nozzles 14 but are inclined forwardly in-

stead of rearwardly so that they will deliver the flushing jets of water in the direction of the movement of the train and ahead of the tender wheels.

35 It will be apparent that my several devices shown are controllable so that they can be used under proper and suitable conditions and that when used they will effectively clean the track of sand before the wheels of the tender and cars travel over the same with the advantages and benefits hereinbefore fully stated.

40 Having thus described my invention, what I claim as new and desire to secure by Letters Patent, is:—

45 The combination with a locomotive and its sanding equipment, of a pipe line leading from the boiler of the locomotive, a valve therein to control the flow of water under pressure through said pipe, and jet nozzles connected to the pipe and disposed one immediately behind each rear driving 50 wheel of the locomotive and at an angle so as to deliver the water jet rearwardly 55 against the rail tread and clean the same of sand immediately behind the driving wheels.

60 In testimony whereof I affix my signature.

JOHN BERRY KELLY.
